UNITED STATES PATENT OFFICE.

CLARENCE HERVY FROELICH, OF BETHLEHEM, AND EARL J. MILLER, OF WARREN, PENNSYLVANIA, ASSIGNORS TO BETHLEHEM STEEL COMPANY.

GUN.

Application filed March 15, 1924. Serial No. 699,434.

To all whom it may concern:

Be it known that we, CLARENCE H. FROELICH and EARL J. MILLER, citizens of the United States, and residing, respectively, at 5 Bethlehem, Northampton County, State of Pennsylvania, and at Warren, Warren County, State of Pennsylvania, have invented new and useful Improvements in Guns, of which the following is a specification.

10 Our invention relates to guns and it has for an object to provide improved recoil mechanism for use between a gun tube and a support or carriage.

15 More particularly our invention has for an object to provide hydraulic and spring means to absorb the energy of recoil of a gun tube together with reliable and effective pneumatic dampening means for checking counter recoil.

20 A further object of our invention is to provide improved supporting means for a gun tube together with a connecting device between the gun tube and the movable recoil element.

25 Apparatus made in accordance with our invention is illustrated in the accompanying drawings, forming a part of this application, in which—

30 Figure 1 is a plan view of our improved gun, showing in dotted lines possible arrangements of the carriage;

Figure 2 is a side elevation of the gun shown in Figure 1;

35 Figure 3 is a detail plan view, on a larger scale, of our improved recoil mechanism;

Figure 4 is a longitudinal sectional view of the apparatus shown in Figure 3 and showing fragmentarily in section and in dotted lines portions of the gun tube;

40 Figure 5 is a front elevation of the apparatus shown in Figure 3;

Figure 6 is a sectional view taken along the line VI—VI of Figure 4; and,

45 Figure 7 is a sectional view taken along the line VII—VII of Figure 3.

Referring now to the drawings more in detail for a better understanding of our invention, in Figures 1 and 2, we show a gun carriage, at 10, upon which is mounted recoil mechanism, at 11, the latter carrying a gun tube, at 12.

50 The recoil mechanism includes an outer cylinder or cradle member 17 having an interlocking guide connection with respect to the barrel portion 18 of the gun, such inter-

locking connection being comprised by a guideway 17' on the outer cylinder or cradle in which fits a supporting portion 18' of the barrel. An inner movable cylinder 19 is arranged within the outer cylinder 17 and it 60 has an upwardly-extending joint portion 20 for connection to the joint portion 21 of the breech ring 22 of the gun tube. The joint member 20 is provided with longitudinal lateral flanges 23 which overlap flanges 65 24 on the joint member 21, the flanges on the two members cooperating to constitute an interlocking guide connection.

The joint portion 20 is provided with an abutment wall 25 at its rear end which is 70 adapted to fit into a recess 26 in the joint portion 21 of the gun tube, the recess having an abutment surface or shoulder 27 adapted to abut the wall 25 when the parts are in assembled relation. Recoil stresses are 75 transmitted from the gun tube to the wall 25 resulting in recoil movement of the gun tube and of the inner recoil cylinder or member 19. As will be pointed out hereinafter, counter-recoil forces are transmitted from 80 the wall 25 to the abutment surface or shoulder 27.

The gun tube is held in place with the abutment surface 27 of the joint portion 21 in contact with the abutment wall 25 of the joint portion 20, by any suitable latch or key means. For example, we show apparatus for this purpose such as disclosed and claimed in the application of Clarence H. Froelich, Serial No. 695,155, filed Feb. 26, 90 1924, such apparatus, in brief, consisting of a recess 29 extending longitudinally of the bottom of the joint portion 21 and having spiral threads 30 adapted to engage with the mutilated threaded portion 31 of the 95 shaft 32 journaled in the lower joint member 20. The shaft 32 is turned by a handle 33. When the gun tube is to be removed or placed in position, the shaft 32 is turned to disengage the threads, whereupon the tube 100 is free to be slid on or off.

The outer recoil cylinder or cradle 17 is open at the top at the rear end and it is formed as a U-shaped guide portion 34 for the joint portion 20 of the inner movable recoil cylinder 19.

The hydraulic dampening or checking apparatus of the recoil mechanism includes a stationary piston 35 carried by a rod 36 extending through a gland 37 at the forward 110

end of the inner cylinder and being connected to the forward closure member 38 for the outer cylinder 17. The rear end of the inner cylinder is closed. Longitudinal grooves 39 extend from the rear end of the inner cylinder, diminish in cross-sectional area at 40 toward their forward ends and terminate in the cylindrical portion 41 at an intermediate point of the inner cylinder. The 10 inner cylinder 19 is filled with any suitable liquid such as oil. Recoil of the gun tube results in rearward movement of the inner cylinder 19 which movement is resisted by the restricted passage of fluid through the 15 grooves 39 from the front side to the rear side of the piston 35. Recoil movement continues, the passage of fluid being restricted as the portions 40 of the grooves of diminishing cross-sectional area pass by the piston and recoil movement ceases when the piston enters the cylindrical portion 41.

Recoil movement is resisted not only by the hydraulic mechanism just referred to but also by a spring device 43 arranged between the forward end of the inner cylinder and the piston 35. This spring device absorbs and stores a portion of the energy of recoil for the purpose of moving the inner cylinder and gun tube back to normal position after recoil. We show the spring device as comprised by inner spring sections 44 and 45 which are spaced by an intermediate spacing member 46 having a slight clearance with respect to the rod 36 and the inner cylinder 19. Making the spring in sections is advantageous from the standpoints of manufacture, assembly, and operation. With the spring device made in sections, buckling is reduced; and the centralized seating and spacing member 46 resists lateral displacement of the springs.

We utilize air to dampen or check counter-recoil movement. To this end, the outer cylinder 17 is provided near its forward closed end with a throttling port or passage 47 and with a main air admission passage 48 disposed rearwardly of the passage 47 and near the end of the recoil stroke of the inner cylinder 19. Upon recoil movement, the inner cylinder first uncovers the passage 47 and air flows into the expansible chamber in the outer cylinder between the forward end of the latter and the forward end of the inner cylinder. However, due to the small size of the port 47, pressure in the expansible chamber continues at a low point until the inner piston passes over the admission port or passage 48, whereupon air rushes into the outer cylinder, filling the expansible chamber, this result being assisted by the pause necessarily occurring at the end of the recoil stroke and the beginning of the counter-recoil stroke. It will be understood that, while we show one throttling port, any number of ports of suitable sizes

may be used for accomplishing the result of assisting in checking counter-recoil.

Upon counter-recoil, the inner cylinder 19 first covers the passage 48 and thereafter the velocity of counter-recoil is checked by the throttled outlet of air permitted by the small passage 47. The inner cylinder 19 covers the throttling passage 47 before the end of its counter-recoil stroke, whereby the air impounded in the expansible chamber serves to cushion the final portion of the movement of the inner cylinder 19 and the gun tube to normal position.

Cushioning of the counter-recoil is also assisted by the cylinder 49 carried by the closure 50 for the forward end of the cylinder and extending within the outer cylinder 17. The inner cylinder 19 carries a piston portion 51 at its forward end of smaller diameter than the main portion of the inner cylinder and adapted to fit the cylinder 49. The piston portion 51 conveniently serves as a housing for the gland 37. The cylinder 49 and the piston 51 are preferably of such lengths that the piston 51 enters the cylinder 49 before the throttling passage 47 is covered, whereby air is impounded in the cylinder 49 and serves to assist in cushioning the last stage of counter-recoil movement.

In addition to the throttled flow of air and the resulting pressure resisting counter-recoil movement, the latter is also checked by the passage of fluid through the grooves 39 from the rear to the front side of the piston 35.

From the foregoing, it will be seen that we have devised simple and effective recoil and counter-recoil mechanism, the energy of recoil being absorbed by a spring device and by a hydraulic fluid check arrangement, the energy absorbed by the spring device being used after the recoil movement to return the gun tube and movable recoil element back to normal position. The inner and outer cylinders cooperate as an air check, which, together with the hydraulic device, effectively checks and dampens counter-recoil movement. It will also be seen that we have devised a simple and effective connection between the gun tube and the recoil mechanism.

Having thus described the invention what we claim as new and desire to secure by Letters Patent is:

1. In a gun, the combination of a cradle having a lower longitudinally extending outer cylinder, an inner cylinder fitting the bore of the outer cylinder, a gun tube, an interlocking guide connection between the upper side of the cradle and the lower side of the gun tube, means for connecting the breech end of the gun tube to the rear end of the inner tube, and means carried by the outer tube and cooperating with the interior of the inner tube for resisting recoil move-

ments of the gun tube and of the inner tube.

2. In recoil mechanism for a gun, the combination of an outer supporting cylinder having a closed forward end, an inner cylinder

5 fitting the bore of the outer cylinder and having a closed rear end and adapted to contain fluid, a rod carried by the outer cylinder and extending in the inner cylinder to a point near the closed end of the latter 10 when the parts are in normal position, a gland carried by the forward end of the inner cylinder and fitting the rod, a piston carried by the rear end of the rod, and means for first restricting and then cutting off the 15 flow of fluid past the piston upon recoil movement of the inner cylinder.

3. In recoil mechanism for a gun, the combination of an outer supporting cylinder having a closed forward end, an inner cylinder 20 having a closed rear end and adapted to contain fluid, a rod carried by the outer cylinder and extending in the inner cylinder to a point near the closed end of the latter when the parts are in normal position, a gland carried by the forward end of the inner cylinder and fitting the rod, a piston carried by the rear end of the rod, and longitudinal grooves extending from the rear portion of the inner cylinder and terminating 25 at an intermediate region thereof.

4. In recoil mechanism for a gun, the combination of an outer supporting cylinder having a closed forward end, an inner cylinder 30 fitting the bore of the outer cylinder and having a closed rear end and adapted to contain fluid, a rod carried by the outer cylinder and extending in the inner cylinder to a point near the closed end of the latter when the parts are in normal position, a gland carried by the forward end of the inner cylinder and fitting the rod, a piston carried by the rear end of the rod, means for restricting the passage of fluid past the piston upon movement of the inner cylinder, 35 spring means for resisting rearward movement of the inner cylinder, and pneumatic means for resisting and cushioning forward movement of the inner cylinder.

5. In recoil mechanism for a gun, the combination of an outer supporting cylinder having a closed forward end, an inner cylinder 40 having a closed rear end and adapted to contain fluid, a rod carried by the outer cylinder and extending in the inner cylinder to a point near the closed end of the latter when the parts are in normal position, a gland carried by the forward end of the inner cylinder and fitting the rod, a piston carried by the rear end of the rod, means for 45 restricting the passage of fluid past the piston upon movement of the inner cylinder, spring means between the forward end of the inner cylinder and the piston, a throttling air passage near the forward end of the outer cylinder, and an air admission pas-

sage extending through the wall of the outer cylinder and disposed rearwardly of the throttling passage.

6. In recoil mechanism for a gun, the combination of an outer supporting cylinder 50 having a closed forward end, an inner cylinder having a closed rear end and adapted to contain fluid, a rod carried by the outer cylinder and extending in the inner cylinder to a point near the closed end of the latter 55 when the parts are in normal position, a gland carried by the forward end of the inner cylinder and fitting the rod, a piston carried by the rear end of the rod, longitudinal grooves extending from the rear portion 60 of the inner cylinder, diminishing in cross-sectional area toward their forward ends, and terminating at an intermediate region of said inner cylinder, spring means between the forward end of the inner cylinder 65 and the piston, a throttling port extending through the wall of the outer cylinder and adapted to be covered by the inner cylinder near the end of the counter-recoil stroke of the latter, and an air admission port extending through the wall of the outer cylinder and adapted to be uncovered by the inner cylinder during its recoil movement.

7. In recoil mechanism for a gun, the combination of an outer supporting cylinder having a closed forward end, an inner cylinder 70 having a closed rear end and adapted to contain fluid, a rod carried by the outer cylinder and extending in the inner cylinder to a point near the closed end of the latter when the parts are in normal position, a gland carried by the forward end of the inner cylinder and fitting the rod, a piston carried by the rear end of the rod, means 75 for restricting the passage of fluid from one side to the other of the piston upon movement of the inner cylinder, a spring device consisting of spring sections with an intermediate seat and spacing member having 80 close clearance with respect to the inner cylinder and the rod, said spring device being interposed between the piston and the inner cylinder, and means for pneumatically 85 cushioning counter-recoil movements of the inner cylinder.

8. In recoil mechanism for a gun, the combination of an outer supporting cylinder having a closed forward end, an inner cylinder 90 having a closed rear end and adapted to contain fluid, a rod carried by the outer cylinder and extending in the inner cylinder to a point near the closed end of the latter when the parts are in normal position, a gland carried by the forward end 95 of the inner cylinder and fitting the rod, a piston carried by the rear end of the rod, means for restricting the passage of fluid from one side to the other of the piston upon movement of the inner cylinder, a 100

spring device consisting of spring sections with an intermediate seat and spacing member, said spring device being interposed between the piston and the inner cylinder, 5 and means for pneumatically cushioning counter-recoil movements of the inner cylinder.

9. In recoil mechanism for a gun, the combination of a supporting outer cylinder 10 having a main cylindrical bore portion and a bore portion of smaller diameter, an inner cylinder for attachment to a gun and having a main cylindrical portion fitting the main bore portion of the outer cylinder and 15 a cylindrical portion of smaller diameter to fit the smaller bore portion of the outer cylinder, a piston in the inner cylinder and connected to the outer cylinder, said inner cylinder adapted to contain fluid, means for 20 restricting the passage of fluid from one side of the piston to the other upon movement of the inner cylinder, a spring device for resisting rearward movement of the inner cylinder, a throttling passage extending 25 through the wall of the outer cylinder near the forward end of the main cylindrical bore portion, and an air admission passage extending through the wall of the outer cylinder and disposed rearwardly of the 30 throttling passage.

10. The combination, with a gun having a carriage and a gun tube, of recoil mechanism comprising an outer cylinder connected to the carriage, an inner cylinder fitting the bore of the outer cylinder and connected to the tube, a piston in the inner cylinder and connected to the forward end of the outer cylinder, means for restricting the flow of fluid from the front to the rear side 40 of the piston upon rearward or recoil movement of the inner cylinder, means for returning the inner cylinder to normal position after recoil movement, and means dependent upon rearward movement of the inner cylinder relatively to the outer cylinder for admitting air to the interior space of the outer cylinder at the forward end of the inner cylinder for dampening return movement of the inner cylinder to normal 45 position.

11. The combination, with a gun having a carriage and a gun tube, of recoil mechanism comprising an outer cylinder connected to the carriage, an inner cylinder fitting the bore of the outer cylinder and connected to the tube, a piston in the inner cylinder and connected to the forward end of the outer cylinder, a spring between the piston and the outer end of the inner cylinder, means for restricting the flow of fluid from the front to the rear side of the piston upon recoil movement of the inner cylinder, and means dependent upon rearward movement 55 of the inner cylinder relatively to the outer

cylinder for admitting air to the interior 65 space of the outer cylinder at the forward end of the inner cylinder for dampening return movement of the inner cylinder to normal position.

12. A gun comprising a carriage, recoil mechanism including relatively stationary and movable elements, a gun tube, an interlocking guide connection between the tube and the stationary element, overhanging tongue-and-slot connections between the tube and the movable element and extending longitudinally thereof, and means for locking the tube in place with respect to the movable element to prevent relative longitudinal movement therebetween. 70

13. The combination, with a gun having a carriage and a gun tube provided with a joint member at its breech end, of recoil mechanism comprising an outer cylinder connected to the carriage, an interlocking guide connection between the tube and the outer cylinder, an inner cylinder within the outer cylinder and having a joint member at the rear end thereof projecting laterally from said outer cylinder, an interlocking 85 guide connection between the joint members, abutment means carried by the joint members, and means for locking the tube in place with respect to said portion after the abutment means are engaged. 90

14. The combination, with a gun having a carriage and a gun tube provided with a joint member at its breech end, of recoil mechanism comprising a cylinder connected to the carriage, an interlocking guide connection between the tube and the outer cylinder, an inner cylinder within the outer cylinder and having a joint member at the rear thereof projecting laterally from said outer cylinder, an interlocking guide connection between the joint members, abutment means carried by the joint members for limiting rearward movement of the tube with respect to the inner cylinder to a predetermined extent, locking means carried by the joint members for locking them together after the abutment means are engaged, a piston in the inner cylinder and connected to the forward end of the outer cylinder, a spring between the piston and the outer end 100 of the inner cylinder, and means for restricting the flow of fluid from the front to the rear side of the piston upon rearward movement of the inner cylinder. 105

15. The combination, with a gun having a carriage and a gun tube, of recoil mechanism comprising an outer cylinder connected to the carriage, said outer cylinder having a main cylindrical bore portion and a forward cylindrical bore portion of smaller 115 diameter, an inner cylinder connected to the tube having a main cylindrical portion fitting the main cylindrical bore portion of the 120

- outer cylinder and a forward cylindrical portion of smaller diameter adapted to fit the cylindrical bore portion of the outer cylinder of smaller diameter, a piston in the inner cylinder and connected to the forward end of the outer cylinder, a spring between the piston and the outer end of the inner cylinder, means for restricting the flow of fluid from the front to the rear side of the piston upon recoil movement of the inner cylinder, a throttling port extending through the wall of the outer cylinder rearwardly of the cylindrical bore portion thereof of smaller diameter, and an air admission port extending through the wall of the outer cylinder and disposed rearwardly of the throttling port and adapted to provide for the rapid filling of the outer cylinder forwardly of the inner cylinder upon being uncovered by the latter.
16. The combination, with a gun having a carriage and a gun tube, of recoil mechanism comprising an outer cylinder connected to the carriage, an interlocking guide connection between the outer cylinder and the gun tube, said outer cylinder having a main cylindrical bore portion and a bore portion of smaller diameter at its forward end, an inner cylinder having a main portion fitting the main cylindrical bore portion of the outer cylinder and forward portion of smaller diameter adapted to fit the cylindrical bore portion of the outer cylinder of smaller diameter, a lateral projection carried by the inner cylinder and extending above the outer cylinder, abutment means carried by the tube and adapted to abut said projection, an interlocking guide connection between the tube and said projection, locking means for holding the tube in place with respect to said projection with the abutment means in abutment therewith, a piston in the inner cylinder and connected to the forward end of the outer cylinder, spring means between the piston and the outer end of the inner cylinder, means for first restricting and then cutting off the flow of fluid from the front to the rear side of the piston upon recoil movement of the inner cylinder, a throttling port extending through the wall of the outer cylinder and spaced rearwardly from the bore portion thereof of smaller diameter a distance less than the length of the cylinder portion of smaller diameter of the inner cylinder, and an air admission port extending through the wall of the outer cylinder and disposed rearwardly of the throttling port, said air admission adapted to be uncovered by the inner cylinder upon recoil movement of the latter in order to rapidly fill the resulting space between the cylinders with air.
17. The combination, with a gun having a carriage and a gun tube, of recoil mechanism comprising stationary and movable elements, an interlocking guide connection between the tube and the stationary element and extending longitudinally thereof, an interlocking guide connection between the tube and the movable element and extending longitudinally thereof, abutment means for limiting rearward movement of the tube with respect to said movable element, and locking means for holding the tube in place with respect to the movable element with the abutment means in engagement.
18. The combination, with a gun having a carriage and a gun tube, of recoil mechanism between the carriage and the tube including an outer cylinder connected to the carriage, an inner cylinder connected to the tube, a rod connected to the outer cylinder and extending within the inner cylinder, a piston carried by the rod and fitting within the inner cylinder, a packing gland at the forward end of the inner cylinder and fitting the rod, spring means between the forward end of the inner cylinder and the piston, said inner cylinder having longitudinal grooves extending for a portion of the length thereof and diminishing in cross-sectional area toward their forward ends, a throttling port in the outer cylinder adapted to afford communication between the interior thereof and the atmosphere and spaced a sufficient distance rearwardly of the forward end thereof so as to be overlapped by the inner cylinder when the parts are in normal position and a large port in the outer cylinder and spaced rearwardly of the throttling port to permit the rapid filling of the outer cylinder with air when uncovered by the inner cylinder upon recoil.
19. A gun comprising a carriage, an outer cylinder carried by the carriage and having a closed forward end, an inner cylinder within the outer cylinder and having a closed rear end, a rod connected to the forward end of the outer cylinder and extending rearwardly within the inner cylinder, said inner cylinder having interior longitudinal grooves extending from the rear end thereof for a portion of the length of the inner cylinder and diminishing in depth toward the forward ends thereof, a piston carried by the rod and fitting the interior of the inner cylinder, a gland arranged between the forward end of the inner cylinder and the rod, spring means between the forward end of the inner cylinder and the piston, a throttling port extending through the wall of the outer cylinder near the forward end thereof and adapted to be overlapped by the inner cylinder when the parts are in normal position, a large port extending through the wall of the outer cylinder and spaced rearwardly of the throttling port and adapted to be uncovered by the inner cylinder upon recoil movement to provide for the outer cylinder being rapidly filled with air, an

interlocking guide connection between the outer cylinder and the tube, an overhanging tongue-and-slot connection between the tube and the rear end of the inner cylinder and 5 preventing relative lateral movement therebetween, and locking means between the tube and the inner cylinder to prevent relative longitudinal movement thereof.

In testimony thereof I hereunto affix my signature this 12th day of February 1924. 10

CLARENCE HERVY FROELICH.

In testimony thereof I hereunto affix my signature this 10th day of March 1924.

EARL J. MILLER.
